(57) **CLAIM**

The ornamental design for a housing for a measuring apparatus, as shown and described.

DESCRIPTION

FIG. 1 is a right-side isometric view of a housing of the measuring apparatus, the measuring apparatus comprising a flowmeter, a densimeter, and a viscometer, as well as the housing for such meters, rotated about its longitudinal axis; FIG. 2 is a plan view slightly rotated about its longitudinal axis view of the housing of the measuring apparatus of FIG. 1;

FIG. 3 is a front side, downwardly oriented isometric view of the housing of the measuring apparatus of FIG. 1; FIG. 4 is a front side, upwardly oriented isometric view of the housing of the measuring apparatus of FIG. 1; FIG. 5 is a front side, downwardly oriented isometric view of an alternate embodiment of the housing of the measuring apparatus of FIGS. 1-3; and, FIG. 6 is a rear, upwardly oriented isometric view of the alternate embodiment of the housing of the measuring apparatus of FIGS. 1-3.
